MUSICAL DRUM

Charles A. Ross, Chanute, Kans., assignor to Kustom Electronics, Inc., Chanute, Kans., a corporation of Kansas

Filed Sept. 30, 1968, Ser. No. 13,766

Term of patent 14 years

Int. Cl. D17—04

U.S. Cl. D56—1

FIG. 1 is a perspective view of a musical drum showing one form of my new design wherein the side wall is fluted in a direction parallel to the drum axis;

FIG. 2 is a perspective view of a musical drum showing a second form of my new design wherein the side wall is fluted circumferentially;

FIG. 3 is a perspective view of a musical drum showing a third form of my new design wherein the side wall is fluted obliquely from the lower left to the upper right;

FIG. 4 is a perspective view of a musical drum showing a fourth form of my new design wherein the side wall is fluted obliquely from the upper left to the lower right;

FIG. 5 is a perspective view of a musical drum showing a fifth form of my new design wherein the side wall is fluted in a herringbone pattern; and

FIG. 6 is a cross-sectional view thereof taken on line 6—6 in FIG. 1.

I claim:

The ornamental design for a musical drum, as shown and described.
